Application March 14, 1938, Serial No. 195,836

17 Claims. (Cl. 101—251)

This invention relates to a surface decorating machine, and more particularly to a machine for applying a decorative design or tracery to surfaces to be decorated. Machines of this nature are sometimes used to apply a decorative design or coating which simulates natural wood grains, marble, etc., to the surface of other materials, which are more desirable than those being simulated, either because they are less expensive, or because they are more easily adapted for use in the production of articles of manufacture.

The present invention is especially concerned with a decorating machine for decorating the surfaces of workpieces which are difficult to handle, because of their size, weight or shape. The present invention is also concerned with an improved decorating machine, in which comparatively large, and therefore heavy printing roll is used; such machine being arranged to facilitate adjustment of the roll to regulate the printing pressure, without disturbing the workholder, the workholder support, the pattern or the inking mechanism. These, therefore, are the general objects of the present invention.

Another object of this invention is to provide an improved support for a decorating unit, to facilitate the decoration of large or cumbersome workpieces.

30 A further object of the present invention is to provide an improved control mechanism for a surface decorating or graining machine.

Another object of this invention is to provide a decorating machine with an improved work support to facilitate travel of the work relative to the decorating unit, together with a decorating unit so arranged as to enable work to be positioned on and removed from a reciprocating carriage from the same side or opposite sides of the machine, as desired.

Another object of this invention is to provide a decorating machine which will be especially adaptable for decorating workpieces of varying thicknesses.

45 Another object of this invention is to provide a decorating machine which will receive a workholder and progress such workholder through the machine, automatically stopping the movement of the workholder when the work has been decorated.

Other objects of this invention will become apparent from the following description, reference being had to a preferred embodiment of the invention illustrated in the accompanying draw-

ings. The essential novel features of the invention will be summarized in the claims.

In the drawings, Fig. 1 is a side elevation of our improved decorating machine; Fig. 2 is a fragmentary plan view, illustrating the workholder and its supporting mechanism; Fig. 3 is an enlarged plan view of the machine, certain parts being broken away to more clearly illustrate the driving mechanism; Fig. 4 is a vertical section, taken in the plane indicated by the line 4—4 on 10 Fig. 3; Fig. 5 is a sectional view, indicated by the line 5—5 of Fig. 4, the view, however, being swung through a clockwise angle of 90 degrees to facilitate illustration; Fig. 6 is a fragmentary vertical section, the plane of the section being 15 indicated by the line 6—6 on Fig. 3; Fig. 7 is a section similar to Fig. 6, but illustrating the decorating unit in a different position; Figs. 8 to 12, inclusive, are electrical diagrams, illustrating an electrical control mechanism for use with the 20 decorating machine.

Our improved decorating machine comprises a frame 10, in which a decorating unit 12 is mounted for swinging movement about a horizontal axis above the workholder 14, which is reciprocated on 25 fixed guiderails 16, by a motor 18.

The frame 10 comprises a base 20, having upstanding side frame members 21 and 22 at opposite sides thereof. At their upper ends, the side frames are joined by a cross-frame member, such as the shaft 23.

The decorating unit 12, mounted in the base frame 10, for swinging movement about a horizontal axis. The decorating unit is mounted in a supplemental frame, which comprises a pair 35 of frame plates 25 and 26, journalled at their upper ends on the main frame shaft 23 and joined together by suitable cross-frame members 27. The supplemental frame is positioned axially of the shaft 23, by collars 24, which are secured to 40 the shaft, and is positioned radially of the shaft by plungers or jacks 150, carried by the base 20, and hereinafter to be more fully described.

The decorating unit, mounted on the supplemental frame, comprises a pattern 30, an offset 45 or transfer roll 31, doctor blades 32 and 33, for the pattern and transfer rolls, respectively, and an ink applicator for the pattern. The pattern extends about the periphery of a pattern roll 34, which is supported by a shaft 35, journalled in 50 the supplemental frame plates 25 and 26.

The pattern 30 is preferably a photo-engraved intaglio printing plate, and is supplied with ink by an inking roller 36, which is secured to a shaft 37. This shaft is journalled in a pair of arms 38, 55

which, in turn, are journalled on pins 39, carried by respective brackets 40. These brackets are secured to the cross-frame member 27 by bolts 41. Adjusting screws 42, carried by respective arms 38, engage the brackets 40 to swing the arms 38 together with the inking roller about the axis of the pins 39. This aligns the inking roller with the pattern and adjusts the pressure between such roller and the pattern, thereby regulating the amount of ink applied to the pattern.

The inking roller is rotated, as will be herein-after more fully described, and has its lower portion submerged in a graining paste or ink, carried in a reservoir 43, which is secured to the brackets 41, heretofore described.

Any surplus ink applied to the pattern 30 by the inking roller 36 is removed by doctor blade 32. This doctor blade is mounted on a bar 45, journalled in a pair of brackets 46 carried by respective frame plates 25 and 26. The doctor blade may be reciprocated axially relative to the pattern by any well known means, not shown, and is resiliently pressed into engagement with the pattern in the usual manner.

The inked pattern is transferred from the pattern to the transfer roll 31, which is provided with a coating 47 of transfer material, such as the usual glue and glycerin compound. However, in some instances a rubber composition is used. The transfer roll is secured to a shaft 48, journalled in arms 49. The arms or bearings 49 are pivotally mounted on pins 50, carried by the frame plates 25 and 26.

To position the transfer roll, relative to the pattern roll, the bearings 49 are extended outwardly through openings 51 in respective frame plates 25 and 26, and are each positioned relative to such plates by a set of adjustable pins or plungers. One set of these pins is best illustrated in Fig. 4, and as there shown, comprises a pin 53 threadingly mounted in a boss 54 of its respective frame plates 25 or 26, and engage one end of its respective bearing 49. The other pin of the set comprises a plunger 55, which engages the opposite end of the bearing, and is slidably mounted in a bracket 56 secured to the frame plates 25 and 26, as the case may be. Adjustably carried by the plunger 55 is a member 57, which is arranged to be engaged by a cam 59, mounted on a shaft, and which, when the mechanism is in use, is in the position shown in Fig. 4. As there shown, the cam 59 maintains the plunger 55 inwardly, causing its bearing to be gripped between the two pins 55 and 53.

When the graining mechanism is stopped, a handle or lever 61 is swung in a clockwise direction to release the transfer roll. This lever is mounted on a shaft 62, journalled in the frame plates 25 and 26. Drivingly connected with this shaft is a pair of gears 63, which mesh with respective gears 64 on the cam shafts, thus causing the cams to be moved, drawing the respective plungers 55 away from the bearing 49, permitting the roll to swing in a counter-clockwise direction through the influence of gravity.

The ink remaining on the roll 31, after the image has been transferred to the work, is removed by the doctor blade 33. This doctor blade is secured to a shaft 65, supported in suitable bearings 66, carried by respective frame plates 25 and 26. The doctor blade 33 is resiliently maintained in contact with the roll 31, in the usual manner.

The driving mechanism for the various rolls is best shown in Figs. 1, 3 and 4. As there shown,

the motor 18 is connected by a suitable driving belt 65, with a pulley 66, secured to the driven shaft of a speed reduction unit 68. The driving shaft 69 of the change-speed unit 68 carries a sprocket wheel 70, which is drivingly connected by 5 a driving chain 71, with a sprocket wheel 72, secured to a shaft 73, journalled in bearings 74 carried by the base 20. The shaft 73 extends outwardly through an opening in the frame plate 10. Secured to the outer end of this shaft is 10 a bevelled gear 75, which meshes with a similar bevelled gear 76, carried by a vertically extending shaft 77 journalled in bearings 78 carried by the main frame plate 10. The shaft 78 is connected by a universal coupling 79, with a shaft 80, which, 15 in turn, is connected by splines 81, with another shaft 82. The shaft 82 is connected by a universal coupling 83, with a vertically extending shaft 84, journalled in a bearing bracket 84, which is supported by and journalled on the pattern 20 roll shaft 35, heretofore described. Adjacent its upper end, the shaft 84 carries a bevelled pinion 87, which meshes with a bevelled pinion 88, drivingly secured to the pattern roll shaft, thereby driving the pattern roll. 25

The offset and transfer roll is driven from the pattern roll shaft 35. As shown in Fig. 4, a sprocket wheel 90 is drivingly secured to the shaft 35, and is drivingly connected by a driving chain 91 with a sprocket wheel 92, rotatably mounted 30 on one of the pins 50, heretofore described. Drivingly connected to the sprocket wheel 92, and mounted on the same pin 50, is a gear 93, which meshes with a gear 94, drivingly secured to the transfer roll shaft 48. An adjustably mounted 35 idler sprocket 95 engages the chain 91 to maintain the proper tension thereon.

The inking roll 36 is also driven from the pattern roll shaft 35. As shown in Fig. 3, a sprocket 97 is secured to the far end of the shaft 35, and is connected by a driving chain 98, with a sprocket 99, carried by a stub shaft, journalled in a supplemental frame bracket 100. The sprocket 99 carries a gear 101, which constantly meshes with a gear 102, carried by a stub shaft 103, journalled 45 in the supplemental frame. The gear 102 is provided with an axially extending pin 104, to engage a radially extending pin 105, carried by the ink roller shaft 37, thus providing a driving connection between the driving mechanism and the 50 inking roller shaft, which readily permits removal of the inking roller.

As heretofore mentioned, the work is supported on a carriage 14, which is reciprocally mounted on guiderails 16. As shown in Figs. 1 and 2, the 55 guiderails 16 pass between the decorating unit and the base 20 of the machine. These rails may comprise comparatively rigid, tubular members, and are supported by standards 110, carried by the base of the machine, or the machine supporting surface. 60

The carriage 14 comprises a rectangular frame, having longitudinal and transverse frame members 111, reinforced at the corners by gussets 112. Mounted on this frame and extending downwardly therefrom is a series of brackets 114, in which are journalled rollers 115. These rollers are preferably shaped complementary to the rails 16, therewith to maintain the carriage in proper alignment at all times. 70

Mounted on the upper face of the carriage 14 is a second set of brackets 117, which support a series of upstanding rollers 118, which are arranged to permit a workholder 119 to be rolled onto the carriage. The workholder, as shown in 75

Figs. 1 and 4, may be fixed against movement relative to the carriage, by a plunger 120, slidably mounted in a bracket 121 carried by the carriage 14, and are arranged to be moved upwardly to engage an opening in a workholder bracket 122 by a cam 123. The cam is carried by the bracket 121, and is provided with an operating lever 124. A spring 125, interposed between the pin 120 and the bracket 121, serves to maintain the pin in engagement with the cam.

The carriage 14 is reciprocated by the motor 18. As shown in the drawings, and especially Fig. 3, the driven shaft of the speed-reducing unit 68 is provided with a sprocket wheel 125, which is drivingly connected by a chain 126, with a sprocket wheel 127, secured to a jack shaft 128 mounted in bearings 129, carried by the base 20. Splined to the shaft 128 is a clutch sleeve 130. This clutch may be moved axially of the shaft to selectively coat with and drive either gear of a pair of gears 131 and 132, which are rotatably mounted on the shaft.

When the clutch is in the position shown in Fig. 3, the carriage travels in the direction of the arrow there shown. As illustrated, the clutch 130 drivingly connects the gear 131 with the shaft 128. The gear 131 meshes with an idler gear 133, which, in turn, meshes with a gear 134, drivingly secured to a drive shaft 135, mounted in bearings 136, carried by the base 20. Also secured to the shaft 135 is a sprocket wheel 137, which constantly meshes with a sprocket chain 138, secured to the underside of the carriage 14, as indicated in Fig. 4.

When the carriage has travelled in the direction of the arrows in Figs. 1 and 3, a distance such that the work carried by the workholder 119 has, to the left, passed beyond the transfer roll 31, an arm 139 secured to the right-hand end 40 of the carriage 119, engages one arm 140 of a bell crank 136, which is pivotally mounted, as at 141 on the frame 10. The other arm 142 of this bell crank is connected by a link 143, with a slide 144, which carries an upstanding bracket 45 145, provided with pins 146, to engage an annular groove 147, in the clutch 130.

The carriage, in its travel towards the left, Figs. 1 and 3, swings the bell crank 140, 142 in a counterclockwise direction, causing the clutch to be shifted from the position shown in Fig. 3 into engagement with the gear 132. This gear meshes directly with a gear 148, which is drivingly secured to the shaft 135, thus reversing the direction of rotation of the sprocket wheel and causing the carriage to move toward the right. When the carriage has moved to the extreme right-hand position, another lever 149, depending from the carriage, as shown in Figs. 1 and 4, engages the bell crank and restores the parts to the position shown in Fig. 3, thus again reversing the driving connection to the carriage.

When a glue and glycerine compound or similar transfer material is used on the transfer roll, it is desirable to limit the printing pressure—that is, the pressure between the transfer roll 32 and the work carried by the workholder 119. This pressure is adjusted by swinging or rocking the decorating unit about the axis of the shaft 23 of the main frame. It will be noted from Figs. 3 and 4 that the offset roll lies to the left of a vertical plane, passing through the pivot axis, namely, the axis of the shaft 23. Thus, the printing unit swings, under the influence of gravity, into contact with the work. This swinging movement is limited by a pair of plungers or jacks 150,

which are mounted in main frame brackets 151 for vertical movement. These plungers engage respective rollers 153, which are carried by stub shafts 154, secured to the respective supplemental frame members 25 and 26. The lower end of each plunger 150 is guided by a bearing 157 carried by the base 20.

Rotation of the plungers or jacks 150 is prevented by pins or bolt 158 (Fig. 4), which extend through the respective bearings 151 and engage slots 159 (Fig. 4) formed in the plungers in the usual manner. To manually raise or lower the plunger, and thus adjust the position of the decorating unit relative to the work, we provide a hand-wheel 160 (Figs. 1 and 3). This hand-wheel is secured to a shaft 161, journaled in the frame plate 21. Secured to the shaft 161 is a sprocket wheel (not shown), but which is drivingly connected by a chain 162, with a sprocket wheel 163, secured to a shaft 164 journaled in the frame plates 21 and 22. Secured to this shaft is a pair of gears 165, which mesh respectively with gears 166, carried by shafts 167, which are journaled in respective bearing members 157, heretofore mentioned. Drivingly secured to each shaft 167 is a bevelled pinion 168, arranged to constantly mesh with a bevelled pinion 166, which threadingly engages its respective plunger 150. Thus, when the hand-wheel is operated, the plungers are raised or lowered, consequently moving the transfer roll towards or from the workpiece, thus limiting the printing pressure. It is apparent that after the carriage has moved to the extreme left-hand position, the hand-wheel may be operated to swing the decorating unit in a clockwise direction about the shaft 23, thus raising the transfer roll above the decorating plane to permit the carriage and the workholder 118 to move toward the right, without danger of contact between the transfer roll and the decorated workpiece.

To enable the position of the transfer roll to be adjusted to individual workpieces, which may vary in height, thus varying the decorating plane and still maintain the proper printing pressure, we have secured to one of the plungers 150, as indicated in Fig. 4, a bracket 170, carrying an arm 171, on which an indicator 172 is pivotally mounted. The decorating unit is moved so that the lowest surface of the transfer roll is in the same horizontal plane as the surface to be decorated, whereupon the printing pressure will be the same, regardless of the vertical position of the surface to be decorated. It will be noted that the arm 170 is adjustably positioned on the plunger 150, to the end that the pressure may be adjusted for climatic or other variable conditions, other than the height of the work surface rotation to the guide-rails 16.

As heretofore mentioned, the decorating machine with which this invention is concerned, is especially adapted for the decoration of a workpiece which varies in thickness, such as is indicated by the dotted line W₁ in Fig. 1. When such workpieces are to be decorated, a transfer roll, having a rubber composition surface coating is generally used, as with such a coating the printing pressure may be much greater than when a glue and glycerine compound is used. The plungers 150 are then adjusted to permit decoration of the lowest point of the surface to be decorated. The workpiece will then swing the unit according to the thickness of the workpiece.

When the irregularities are the same in all workpieces, as sometimes is the case, a glue and

glycerine composition transfer roll is preferably used, as better results may be obtained thereby. In such instances, a pair of rollers or discs, one of which is indicated by the dotted lines 275 in Fig. 3, are secured to opposite ends of the offset roll. These discs coat with fixed cam rails 276, carried at opposite sides of the workholder, to positively raise and lower the decorating unit. The surface contour of the cam rails is substantially identical with the surface contour of the work—hence a predetermined printing pressure may be maintained.

When the machine is used continuously on similar workpieces, that is, workpieces which are all of the same thickness or which are so mounted on their workholders that the surfaces to be decorated are the same distance above the carriage 14, we may provide an automatically controlled drive for the carriage and for swinging the decorating unit about its axis to raise and lower the transfer roll, and thus permit the work, after being decorated, to be returned to the right-hand side of the machine (Fig. 4), without disturbing the freshly inked impression.

The automatically controlled drive includes a motor 250 for reciprocating the carriage and a second motor 200. The motor 200 may be connected to the plunger drive shaft 164, in any well known manner, as, for instance, by a gear reduction unit similar to that shown at 68 in Fig. 4, but having its driven shaft drivingly connected with the shaft 164.

When the automatic control is used, both the motor 250 and the motor 200 are reversing type motors and the clutch mechanism, heretofore described in connection with Fig. 3, is eliminated. A gear reduction unit (not shown) is drivingly connected between the motor 250 and the carriage sprocket wheel drive shaft 135. The motor 18 then functions only to drive the decorating rolls. The motors 250 and 200 are controlled by electric circuits and switches illustrated in Figs. 8 to 12, inclusive, and including a pair of reversing switches 201 and 202, respectively. The switch 201 controls the carriage motor, and is operated by the carriage bars 139 and 149 which, when the clutch mechanism is used, control such clutch as heretofore described. The switch 202 controls the jack operating motor 202 and is actuated by the movement of the plungers, the arm of such switch being arranged to be engaged by the arm 171, which, as heretofore described, is carried by one of the jacks 150.

Each of the switches 201 and 202 are of the reversing type—that is, they are arranged to control their respective motors, so as to reverse the direction of rotation of the motors. The circuit to each motor, however, is made through the switch of the other motor, so that while the respective motor switches control the direction of rotation of their respective motors, the flow of current to each motor is controlled by the other switch for the other motor.

The circuits are best illustrated in Figs. 8 to 12. As there shown, Fig. 8 illustrates the circuits when the carriage is at rest in the right-hand or loading position. When the carriage is loaded, a manual switch member 204, associated with the switch 202, as will hereinafter be more fully described, is manually moved from the position shown in Fig. 8 to the position shown in Fig. 9. This causes a circuit through the motor 18 to be made. As shown in Fig. 9, this circuit is made from the main line 210 through a line 211, to one member 212 of the switch 201. From there,

through lines 213 to the motor, and thence through a line 214, to another switch member 215 of the switch 201, thence through a line 216a, to the manually operable switch 204, heretofore described, which is connected by a line 216, with the other main line 217. The field of the motor 250 is connected between the line 211 and a line 218, which is connected to the main line 217. In this instance, the direction of the carriage-moving motor is indicated by the arrow and is such as to cause the carriage to travel toward the left, thus performing the decorating operation.

As the carriage reaches the extreme left-hand position, the arm 139 thereof moves the switch arm of the switch 201 from the position shown in Fig. 9, to the position shown in Fig. 10. This switch connects the line 211 with the switch member 215, thence through the line 214 to the motor 250, and from thence through the line 213, the switch member 212 and a line 220 with a switch point 221 of the switch 202. This switch, however, is in such a position that the switch point 221 is open. Thus, the circuit to the motor 250 is cut. However, as when the switch member 201 was shifted to the position shown in Fig. 10, the lines 217 and 218 were connected by a switch member 222 of the switch 201, with a line 223, and a switch member 224 of the switch 202, with a line 225, leading to the motor 200, and thence through a line 226, a switch member 227, of the switch 202, with the line 228, which is connected with a main line 210, thus energizing the motor 200 to rotate in the direction of the arrow shown in Fig. 10, causing the jacks or plungers to be raised.

When the plungers have been raised a predetermined distance, sufficient to cause the transfer roll to clear the work, they actuate the switch member 202 to move the switch member 202 from the position shown in Figs. 8, 9 and 10, to the position shown in Fig. 11, in which position the manual switch member 204 has been moved by the switch 202 to contact with the contact point 221, thus energizing the circuit to the motor 250, and causing it to operate in a reverse direction, as indicated by the arrow in Fig. 11, returning the carriage to an extreme right-hand position.

The movement of the switch member 202, above mentioned, from the position shown in Fig. 10 to the position shown in Fig. 11, operates the switch members 224 and 227 of the switch 202 to reverse the flow of current through the motor 200. However, the switch member 227, under such reversing condition, is connected with a switch point 230, which, in turn, is connected with a switch point 231 of the switch 201, which at this time is not engaged by any switch member of the switch 201. Therefore, the circuit to the motor 200 is open, and thus the movement of the lifting jack is stopped.

When the carriage reaches the extreme right-hand position, the switch 201 is moved, by the depending arm 149 of the carriage, from the position shown in Fig. 11 to the position shown in Fig. 12. This causes the switch member 222 to engage the switchpoint 231, thus coupling the motor 200 with the line 218, and thus with the power line 217, thereby energizing the motor 200, causing it to rotate in the direction of the arrow in Fig. 12, thus lowering the jack and permitting the decorating unit to return to its normal or decorating position.

When the jacks have been lowered a predetermined distance, the arm 171 thereof contacts the switch member 202, moving it from the position

- shown in Fig. 12 to the position shown in Fig. 8. This reverses the direction of the flow of current through the motor 200, but inasmuch as the switch member 227, through which current must pass in order to energize the motor 200, is connected by a line 240, with a switchpoint 241 of the switch 201, which point is not contacted by any member of such switch, the circuit to the motor 200 is opened.
- 10 The connection between the switch 202 and the member 204 is a lost motion connection, so that as the switch moves from the position shown in Fig. 12 to the position shown in Fig. 8, the switch member 204 is not moved a distance sufficient to cause it to contact with the line 216, thus the circuit to the carriage motor remains opened until the switch 204 is manually operated. This permits the removal of a decorated piece from the carriage and the positioning of an undecorated piece thereon, whereupon the switch 204 may be manually operated and the cycle of operation again renewed.
- When the work is placed on the carriage on one side of the machine, for example, on the right-hand side and moved to the left-hand side to be decorated, and removed from the workholder at the left-hand side of the machine, it may be desirable to cause a dwell of the carriage before its direction of movement is reversed. If this is desired, the switch-point 221, shown in Figs. 8 and 9, may be moved to the position shown by the dotted line 221a (Fig. 11), whereupon the movement of the switch arm 202, due to the lost motion connection between it and the arm 204, will move the switch-point 204 to the position shown in the drawings. Inasmuch as the switch-point 221 has been moved, no circuit will be made until the switch member 204 is manually moved into contact with the switch-point 221a.
- 40 Obviously, both the switch members 201 and 202 are of the type generally known as snap switches—that is, they are actuated, for instance, by a dead-center spring, so that they will not move from the contact in one position until the spring has been sufficiently compressed to carry them to their other contacting position, regardless of the fact that motion of either the jack or the carriage is entirely stopped when one contact is broken.
- 50 From the foregoing description, it will be seen that we have provided a simple and efficient decorating machine, especially adapted for the decoration of large and/or cumbersome articles of manufacture, which mechanism is readily adjustable to regulate the printing pressure, and wherein work may be positioned on the machine and removed from the mechanism at the same side of the machine, and wherein the mechanism is so controlled that the action of the work carriage from the time the work is positioned thereon until the work is returned in a discharged position, is entirely automatic.

We claim:

1. In a decorating machine, a main frame, a pattern roll and a transfer roll carried by said frame, a guideway, a workholder mounted for movement along said guideway, power means to progress said workholder, and means carried by said workholder and acting on said power means to stop the movement of said workholder.
- 65 2. In a decorating machine, a main frame, a pattern roll and a transfer roll carried thereby, a guideway, a workholder mounted for reciprocating movement along said guideway, power means to reciprocate said workholder and means car-

ried by said workholder and acting consequent upon a predetermined movement of the workholder in either direction to disconnect said power means from said workholder.

3. In a decorating machine, a main frame, a pattern roll and a transfer roll carried thereby, a guideway, a workholder mounted on said guideway, a rack carried by said workholder, a gear carried by said frame and in engagement with said rack, means to rotate said gear including a clutch having a neutral position, and means actuated by said workholder to move said clutch to its neutral position consequent upon a predetermined movement of the workholder.

4. In a decorating machine, a main frame, a printing roll carried thereby, a guideway, a workholder mounted on said guideway, a rack carried by said workholder, a gear carried by said frame and in engagement with said rack, means to selectively rotate said gear in opposite directions including a clutch having a neutral position, and means actuated by said workholder to move said clutch to its neutral position consequent upon a predetermined movement of the workholder in either direction.

5. In a decorating machine, a decorating unit, a printing roll, a guideway extending in a direction transverse to the axis of the printing roll, a carriage having wheels adapted and arranged to coact with said guideway, means to reciprocate said carriage along said guideway, a workholder, and means to lock said workholder in a predetermined position on said carriage.

6. In a decorating machine, a decorating unit, a printing roll, a guideway extending in a direction transverse to the axis of the printing roll, a carriage having wheels adapted and arranged to coact with said guideway, means to reciprocate said carriage along said guideway, a workholder, anti-friction means disposed between said workholder and said carriage to facilitate the sliding of the workholder to and from said carriage, and means to lock said workholder in a predetermined position on said carriage.

7. In a decorating machine, a main frame, a supplemental frame pivotally mounted therein, a printing roll carried by said supplemental frame, a workholder, means to progress the workholder past the printing roll, means to swing the supplemental frame about its pivot to move the transfer roll toward or away from the impression plane of work carried by the workholder, an indicator carried by said last-named means and coacting with said workholder before the workholder has advanced to printing position to indicate the position of the printing roll relative to the impression plane of work carried by the workholder, said indicator being adjustably secured to said means whereby it may be moved a predetermined distance out of such plane to thereby permit a predetermined printing pressure to be maintained.

8. In a decorating machine, a main frame, a supplemental frame, a pattern roll and a transfer roll carried by said supplemental frame, means to rotate said rolls, a guideway, a workholder mounted for reciprocating movement on said guideway, means to reciprocate said workholder, said supplemental frame being mounted to swing to and from said guideway.

9. In a decorating machine, a main frame, a pattern roll and a transfer roll carried by said frame, a guideway, said transfer roll being movable toward and from said guideway, a reciprocable workholder mounted on said guideway, and

means to rotate said rolls, means to reciprocate the workholder, and means to move said transfer roll.

10. In a decorating machine, a main frame, a pattern roll and a transfer roll carried thereby, a guideway, said transfer roll being movable toward and from said guideway, a workholder mounted for reciprocating movement along said guideway, power means to reciprocate said workholder and means acting consequent upon a predetermined movement of the workholder in one direction to move said roll in one direction and stop the movement of said workholder.

11. In a decorating machine, a main frame, a pattern roll and a transfer roll carried by said frame, a guideway, said transpare roll being movable toward and from said guideway, a reciprocable workholder mounted on said guideway, and means to rotate said rolls, means to reciprocate 20 the workholder, means controlled by a predetermined movement of said workholder to stop the movement of such workholder, means to move said transfer roll, and means controlled by predetermined movement of said transfer roll to 25 stop the movement of such roll.

12. In a decorating machine, a main frame, a printing roll, a guideway, said roll being mounted for movement toward and from said guideways, a workholder mounted for movement along said 30 guideway, power means to move said roll and means under the control of said roll to move said workholder.

13. In a decorating machine, a guideway, a workholder mounted for reciprocation on said 35 guideway, a printing roll bodily movable toward and away from said guideway, a reversible power mechanism operatively connected to reciprocate said workholder, a second reversible power mechanism operatively connected to move said roll, 40 a reversing means for each motor, said means being operated by predetermined movements of said workholder and roll respectively, and means whereby the reversing means for each mechanism determines the operativeness of the other mechanism.

45 14. In a decorating machine, a guideway, a workholder mounted for reciprocation on said guideway, a printing roll bodily movable toward and away from said guideway, a reversible electric motor operatively connected to reciprocate 50 said workholder, a second reversible motor operatively connected to move said roll, a reversing

switch for each motor, said switches being operated by predetermined movements of said workholder and roll respectively, and means whereby the reversing switch of each motor controls the flow of current to the other motor.

15. In a decorating machine, a guideway, a workholder mounted for reciprocation on said guideway, a printing roll bodily movable toward and away from said guideway, a reversible electric motor operatively connected to reciprocate 10 said workholder, a second reversible motor operatively connected to move said roll, a reversing switch for each motor, means actuated by a predetermined movement of said workholder in either direction to move one of said switches, 15 and means actuated by a predetermined movement of said roll in either direction to move the other of said switches, and means whereby the reversing switch of each motor determines whether or not current will flow to operate the 20 other motor, and a manually operable starting switch.

16. In a decorating machine for decorating surfaces which deviate from a common plane, a main frame, a supplemental frame carrying a 25 decorating unit, a workholder, means to progress the workholder past the decorating unit, said supplemental frame being mounted in the main frame to swing toward and away from the path of the workholder, and a cam carried by said 30 workholder and coacting with the supplemental frame to swing the supplemental frame, said cam deviating from a common plane substantially the same as the work deviates from a common plane.

17. In a decorating machine, a main frame, a supplemental frame mounted on the main frame to swing about a horizontal pivot, a pattern roll mounted in said supplemental frame, a pattern inking mechanism carried by said supplemental frame, a transfer roll carried by the supplemental frame and coacting with said pattern, a workholder, means to progress the workholder through the machine, said supplemental frame being arranged and adapted to swing under the influence of gravity into contact with a workpiece, carried 40 by said workholder, means to limit the swinging movement of said supplemental frame toward the workholder and means carried by the workholder to control the swinging movement of said supplemental frame.

EDWARD WILLIAM HAMANT.
GUIDO von WEBERN.
